UNITED STATES PATENT OFFICE.

JOHAN MACHEK, OF WAUKEGAN, ILLINOIS.

CLUTCH.

1,161,943.

Specification of Letters Patent. Patented Nov. 30, 1915.

Application filed February 20, 1914. Serial No. 819,921.

To all whom it may concern:

Be it known that I, JOHN MACHEK, a citizen of the United States, and a resident of the city of Waukegan, county of Lake, and 5 State of Illinois, have invented certain new and useful Improvements in Clutches, of which the following is a specification.

My invention relates to improvements in friction clutches and has for its object the 10 production of a clutch of this character especially designed for use in connection with phonographs, which will be of durable and economical construction and efficient in operation.

15 Other objects will appear hereinafter.

The invention consists in the combinations and arrangements of parts hereinafter described and claimed.

The invention will be best understood by 20 reference to the accompanying drawing forming a part of this specification, and in which,

Figure 1 is a top plan view, partly in section, of a clutch embodying my invention, 25 and Fig. 2 is a section taken on line $x-x$ of Fig. 1.

The preferred form of construction as 30 illustrated in the drawing comprises a shaft 1 upon which is arranged a disk 2 fixed to said shaft by means of a key 3. Arranged at opposite sides of the disk 2 are rocker arms 4 the inner ends of which pivotally embrace the shaft 1. Cooperating with the outer ends of rocker arms 4 is a lever 5 pivotally connected at its inner end with the 35 outer ends of said rocker arms by means of a pin 6. The lever 5 is so arranged that the inner end 7 thereof is positioned in close proximity with the periphery of disk 2, said end however being out of engagement with 40 said disk periphery when lever 5 is in radially extending position. Said end 7 is eccentrically disposed relative to the pivot or center of oscillation of said lever so that 45 when said lever is tilted in either direction from its radial or neutral position, the former will engage with the periphery of disk 2 so as to effect operative connection between said disk and lever through frictional engagement.

50 The lever 5 is releasably held in either of its three positions, namely neutral position or in tilted position to the right or left of neutral position, by means of a leaf spring 8 which is secured at one end to the lever 5 by means of a screw 9. Said leaf spring 8

is held in central position relative to lever 5 by means of stop fingers 10 formed at the outer end of the corresponding rocker arm 4, said stop fingers engaging against the opposite longitudinal edges of said spring intermediate the ends thereof. The free end of spring 8 is provided with an inwardly extending lug 11 adapted, when in central position, to engage a recess 12 provided in the corresponding side of lever 5 and thus serve to hold the latter in its neutral position. When it is desired to tilt the lever 5 in either direction it is only necessary to flex the free end of spring 8 in either direction, 70 the resiliency or tension of the spring serving to tilt the lever as desired. Said spring is releasably locked in either of its flexed positions by engagement of the lug 11 against either of the longitudinal edges of the lever 5, said lug being automatically engaged with said edges of said lever through the resiliency of the spring when said lug is moved from engagement with the adjacent surface of the lever. Said spring 8 is shown in 80 one of its flexed positions and hence the lever 5 in one of its tilted positions in dotted lines in Fig. 1.

When the lever 5 is in either one of its tilted positions it will be seen that an operative connection will be established between the disk 2 and said lever during rotation of said disk in one direction, the connection between said disk and lever being broken upon reverse rotation of said disk. Through the arrangement whereby the lever 5 may be adjusted to tilt in either direction from its neutral position it is apparent that an arrangement is produced whereby operative connection between the disk 2 or the driving element and the lever or the driven element may be established with said driving element rotating in either direction.

The clutch is of simple and economical construction, the same may be readily assembled and hence will be found of low cost to manufacture.

With the construction set forth it will be seen that in the operation of the clutch, with the shaft 1 rotating in either direction, the lever 5 may be operatively connected therewith by simply flexing the spring 8 in one direction or the other to engage the inwardly turned lug 11 thereof with one or the other of the lateral edges of said lever. If it is desired to disconnect said lever from the member 2 it is only necessary to disen-

gage the lug 11 from the lateral edge of said lever engaged by said lug and to engage the outer end of said lug with the recess 12 in said lever, whereupon the latter will be held in neutral position, that is with the inner end thereof out of engagement with the periphery of member 2.

The clutch mechanism disclosed is adapted for use in a large number of places, as for instance in connection with the winding shaft of a phonograph. In this use the lever 5 of the device will serve as the winding crank of the phonograph in connection with which the same is employed, the outer end of said lever being, in this case, provided with a suitable handle. Also the device is especially applicable to a self-player piano in connection with the brake or stop shaft which coöperate with the winding or 20 winding shaft of the music web. It is especially adapted for use in the latter connection because the same is noiseless in its operation and operates in a limited space. Also, the device is especially adapted for 25 use in connection with a carpenter's or machinist's drill, being adapted for adjustment to effect positive rotation of the bit or drill in the drilling operation and for adjustment to effect retrograde rotation of the bit or 30 drill in the removal of the bit or drill from the opening formed in the work operated upon.

While I have illustrated and described the preferred form of construction for carrying my invention into effect, this is capable of variation and modification without departing from the spirit of the invention. I, therefore, do not wish to be limited to the precise details of construction set forth, but 40 desire to avail myself of such variations and modifications as come within the scope of the appended claims.

Having described my invention what I claim as new and desire to secure by Letters 45 Patent is:

1. A device of the class described comprising a rotatably mounted circular element; a member pivotally connected with said circular element concentrically thereof; 50 a lever having one end pivotally connected with said member and arranged for engagement against the periphery of said circular element, said end of said lever, when in one position relative to said element, being in neutral or disengaging position, tilting of said lever in either direction from said neutral position, causing said end thereof to engage said periphery of said circular element; and means for 55 yieldingly holding said lever in either of its tilted positions, substantially as described.

2. A device of the class described comprising a rotatably mounted circular element; a member pivotally connected with said circular element concentrically thereof; a lever 60

having one end pivotally connected with said member and arranged for engagement against the periphery of said circular element, said end of said lever, when in one position relative to said element, being in neutral or disengaging position, tilting of said lever in either direction from said neutral position, causing said end thereof to engage said periphery of said circular element; and resilient means for yieldingly holding said lever in either of its tilted positions, substantially as described. 70

3. A device of the class described comprising a rotatably mounted circular element; a member pivotally connected with said circular element concentrically thereof; a lever having one end pivotally connected with said member and arranged for engagement against the periphery of said circular element, said end of said lever, when in one position relative to said element, being in neutral or disengaging position, tilting of said lever in either direction from said neutral position, causing said end thereof to engage said periphery of said circular element; and a leaf spring for yieldingly holding said lever in either of its tilted positions, substantially as described. 85

4. A device of the character described comprising a rotatably mounted circular element; a rocker arm having one end pivotally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in either direction from said neutral position, causing said end thereof to engage said periphery of said circular element; and means for yieldingly holding said lever in either of its tilted positions, substantially as described. 95

5. A device of the character described comprising a rotatably mounted circular element; a rocker arm having one end pivotally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in either direction from said neutral position, causing said end thereof to engage said periphery of said circular element; and means coöperating with said rocker arm for yieldingly holding said lever in either of its tilted positions, substantially as described. 110

6. A device of the character described comprising a rotatably mounted circular element; a rocker arm having one end pivot- 120

ally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in either direction from said neutral position, causing said end thereof to engage said periphery of said circular element; means for yieldingly holding said lever in either of its tilted positions, said means comprising a leaf spring secured at one end to said lever; means at the outer end of said rocker arm engaging with said spring intermediate its ends to hold said spring in a fixed position, the free end of said spring being adapted for lateral flexing in either direction; and means for holding said free end of said spring in either of its flexed positions, substantially as described.

7. A device of the character described comprising a rotatably mounted circular element; a rocker arm having one end pivotally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in either direction from said neutral position, causing said end thereof to engage said periphery of said circular element; means for yieldingly holding said lever in either of its tilted positions, said means comprising a leaf spring secured at one end to said lever; stop fingers at the outer end of said rocker arm engaging with said spring intermediate its ends to hold said spring in fixed position, the free end of said spring being adapted for lateral flexing in either direction; and means for holding said free end of said spring in either of its flexed positions, substantially as described.

8. A device of the character described comprising a rotatably mounted circular element; a rocker arm having one end pivotally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in either direction from said neutral position, causing said end thereof to engage said per-

iphery of said circular element; means for yieldingly holding said lever in either of its tilted positions, said means comprising a lateral flexible leaf spring, said spring being adapted when flexed in one direction to tilt said lever in one direction and, when flexed in the other direction, to tilt said lever in the other direction; and means for releasably holding said spring in either of its flexed positions, substantially as described.

9. A device of the character described comprising a rotatably mounted circular element; a rocker arm having one end pivotally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in either direction from said neutral position, causing said end thereof to engage said periphery of said circular element; means for yieldingly holding said lever in either of its tilted positions, said means comprising a lateral flexible leaf spring, said spring being adapted when flexed in one direction to tilt said lever in one direction and, when flexed in the other direction, to tilt said lever in the other direction; and a lug at the free end of said spring adapted to engage against either of the longitudinal edges of said lever to releasably lock said spring in either of its flexed positions, substantially as described.

10. A device of the character described comprising a rotatably mounted circular element; a rocker arm having one end pivotally connected with said circular element concentrically thereof; a lever having one end pivotally connected with the outer end of said rocker arm for engagement against the periphery of said circular element, said end of said lever, when in one position relative to said element, being in neutral or disengaging position, tilting of said lever in one direction from said neutral position causing said end thereof to engage said periphery of said circular element; and resilient means for yieldingly holding said lever normally in said tilted position, substantially as described.

In testimony whereof I have signed my name to this specification in the presence of two subscribing witnesses.
